UNITED STATES PATENT OFFICE

2,536,754

DETACHING MOTION

John S. Dudley, Douglas, and Carl D. Brandt,
Whitinsville, Mass.

Application February 19, 1949, Serial No. 77,396

10 Claims. (Cl. 19—116)

1

This application is a continuation-in-part of application, Serial No. 708,740, filed November 8, 1946, now abandoned.

The invention relates to combing machines, and has for its primary object the provision of an improved detaching roll drive or motion of such simplicity, compactness and organization as to be capable of operation with a minimum of vibration and effort, and hence, at high speeds. A further object, contributing to the same general result, is the elimination of play or back-lash such as has characterized prior constructions.

With the foregoing and other objects and advantages in view, as will presently appear, the invention comprises the combinations and arrangements hereinafter described with reference to the accompanying drawings, which exemplify a presently preferred form of the invention. In the drawings:

Fig. 1 is a diagrammatic plan view of a comber, showing the preferred location of the improved detaching roll drive;

Fig. 2 is a broken out, elevational view looking toward the right-hand end of the comber of Fig. 1;

Fig. 3 is a vertical section on the line 3—3 of Fig. 2;

Fig. 4 is a top plan view of the drive (portions of the housing walls being removed to expose the parts); and

Figs. 5, 6 and 7 are vertical sections on the lines 5—5, 6—6 and 7—7, respectively, of Fig. 4 (the background being omitted in Figs. 6 and 7).

In Fig. 1 a comber 1, including end frame members 2 and 3, is shown in more or less standard, general arrangement, a draw box 4 and coiler 5 being indicated at the left. At the right, there is indicated a housing 6 which encloses the roll drive of this invention.

Referring particularly to Fig. 3, it will be seen that the housing just mentioned includes what for convenience will be referred to as "inner" and "outer" side walls 7, 8, the inner wall in this instance constituting a part of the end frame member 2 and the outer wall a cover removably secured to the surrounding, housing wall 9. While it is by no means essential that the drive be wholly enclosed, it is a feature of this preferred form that the organization is adapted to permit the mechanism to be housed, as indicated, in what serves as an oil bath enclosure, so that adequate lubrication at all times is assured, without danger of the lubricant spreading to other parts of the comber and soiling the stock. In Figs. 2 and 3

2

there is shown a sight gauge 9a, by which the oil level is indicated.

The drive shaft for the motion may be the usual comb cylinder shaft 10, at least a portion of which extends between the walls 7, 8. In this instance, the shaft 10 is journaled in these walls and extends beyond the outer wall where, on its free end, it carries a drive pulley 10a. Keyed to shaft 10 between walls 7, 8 is a drive gear 11 which meshes with the teeth 12 of a compound gear 13, sometimes for convenience referred to herein as the first driven gear. Gear 13 is mounted on and, in this instance, free to rotate upon, a second shaft 14 which, like the drive shaft, has at least a portion of its length extending between the walls 7, 8 and preferably, as shown, journaled in those walls and extending beyond the outer wall. In the present embodiment, shaft 14 serves as and is sometimes referred to herein as a rock shaft.

The teeth 17 of compound gear 13 mesh with the teeth 18 of a planet gear member, such as compound gear 19, which is supported by a planet stud 20. The planet stud is, in turn, supported by a planet arm 21 which is mounted on and, in this instance, secured to rock shaft 14. The teeth 22 of the planet gear member mesh with a gear 23, sometimes referred to herein as the second driven gear, which is also mounted on shaft 14. Gear 23, which serves as the roll drive gear, meshes with a pinion 24 secured to the shaft 25 of bottom detaching roll 26. In this instance, as is common, a second bottom detaching roll 27 is indicated, its shaft 28 carrying a pinion 29 which is driven from pinion 24 through a long tooth idler 30 carried by shaft 31. It will be understood that, as usual, the bottom detaching rolls 26, 27 cooperate with upper detaching rolls, the latter being indicated in dotted outline in Fig. 2, and marked 26' and 27', respectively. The pairs of detaching rolls are thus continuously geared to the drive gear 11 and shaft 10.

Secured to shaft 10, adjacent its drive pulley 10a, is a cam which is coupled to the roll drive to effect the oscillation of the planet arm relatively to the driven gears 13, 23. The cam is shown as comprising a wheel 32 incorporating a cam track generally designated 33; and running in the cam track is a cam roll 34, stud-supported in the end of a crank arm 35 secured to rock shaft 14. Oscillation of rock shaft 14 by the cam track and cam roll results in oscillation of planet arm 21 and of compound gear 19 about the axis of rock shaft 14, the described mechanism constituting a planetary drive from gear 11 to the

detaching rolls and adapted, as the result of the orbital movement imparted to compound gear 19, which is the planet of the system, to drive the detaching rolls alternately forward and backward and at speeds determined by the shape of the cam. As will be recognized, the compound form of gears 13 and 19 provides appropriate reduction.

As shown more particularly in Fig. 5, the cam track is more or less kidney-shaped, including a concentric portion 36 extending through slightly more than half the circumferential length of the track, and a re-entrant portion consisting of straight stretches 37, 38 merging at a point 39 of minimum radius and at their outer ends merging smoothly into the ends of the concentric portion. The direction of rotation of shaft 10 and cam track 33 is indicated by the arrows in Figs. 5, 6 and 7.

By reason of the fact that the motion or drive consists of a simple train of components, which can be very closely spaced and which can be well supported immediately on both sides by the adjacent walls 7, 8, a high degree of balance and freedom from whip and vibration are achieved. Also, by mounting all of the gear components between the walls and the cam and crank oscillating mechanism on the outside side of the outer wall, the indicated advantages of adequate lubrication and cleanliness are achieved, while permitting the timing of the motion (which is changed by adjusting the cam track relatively to the follower) to be adjusted without in any way disturbing the rest of the motion.

As will be understood, the details are subject to variation, within the claims, to meet the exigencies of particular situations; and in the light of the foregoing description of a preferred embodiment of the invention, the following is claimed:

1. In a comber, a planetary detaching roll drive comprising: an oil bath housing, including inner and outer side walls; a comb cylinder shaft passing through both walls; a cam wheel mounted on said shaft on the outside of the outer wall; a drive gear secured to said shaft within the housing; a rock shaft journaled in said walls; a first driven gear freely mounted on said rock shaft within the housing and meshing with the drive gear; a second driven gear freely mounted on the rock shaft within the housing; a compound planet gear meshing with both said driven gears; a planet stud, wholly within the housing, supporting the compound planet gear; a planet stud supporting arm secured to the rock shaft within the housing; a crank arm secured to the rock shaft on the outside of the outer wall; and means connecting the crank arm and the cam wheel.

2. In a comber, a planetary detaching roll drive comprising: an oil bath housing, including inner and outer side walls; a comb cylinder shaft passing through both walls; a cam wheel mounted on said shaft on the outside of the outer wall; a drive gear secured to said shaft within the housing; a rock shaft journaled in said walls; a first driven gear freely mounted on said rock shaft within the housing and meshing with the drive gear; a second driven gear freely mounted on the rock shaft within the housing; a compound planet gear meshing with both said driven gears; a planet stud supporting the compound planet gear; a planet stud supporting arm secured to the rock shaft; a crank arm secured to the rock shaft on the outside of the outer wall; and means connecting the crank arm and the cam wheel.

3. In a comber, a planetary detaching roll drive comprising in combination: a first wall; a second, parallel wall; a comb cylinder shaft passing through both walls; a cam wheel mounted on the comb cylinder shaft to rotate therewith; a drive gear secured to the comb cylinder shaft between said walls; a second shaft having at least a portion of its length extending between said walls parallel to the comb cylinder shaft; a first driven gear mounted on the second shaft between the walls and meshing with the drive gear; a second driven gear mounted on the second shaft between said walls; a planet gear member between said walls meshing with both the first and second driven gears; a planet stud supporting the planet gear member; a planet arm mounted on said second shaft and supporting the planet stud; and an oscillator connection between the cam wheel and the planet arm.

4. In a comber, a planetary detaching roll drive comprising in combination: a first wall; a second, parallel wall; a drive shaft having at least a portion of its length extending between said walls; a cam wheel secured to the drive shaft; a drive gear secured to the drive shaft between said walls; a rock shaft having at least a portion of its length extending between said walls parallel to the drive shaft; a first driven gear freely mounted on the rock shaft between the walls and meshing with the drive gear; a second driven gear freely mounted on the rock shaft between said walls; a planet gear member between said walls meshing with both the first and second driven gears; a planet stud supporting the planet gear member; a planet stud supporting arm secured to said rock shaft and supporting the planet stud; and an oscillator connection between the cam wheel and the rock shaft.

5. In a comber, a planetary detaching roll drive comprising in combination: a first wall; a second, parallel wall; a drive shaft having at least a portion of its length extending between said walls; a drive gear secured to the drive shaft between said walls; a second shaft having at least a portion of its length extending between said walls parallel to the drive shaft; a first driven gear mounted on the second shaft between the walls and meshing with the drive gear; a second driven gear mounted on the second shaft between said walls; a planet gear member between said walls meshing with both the first and second driven gears; a planet stud supporting the planet gear member; and a planet stud supporting arm mounted on said second shaft with freedom to oscillate relatively to the driven gears.

6. In a comber, a planetary detaching roll drive comprising in combination: a drive shaft; a drive gear secured to the drive shaft; a second shaft, parallel to the drive shaft; a first driven gear mounted on the second shaft and meshing with the drive gear; a second driven gear mounted on the second shaft; a planet gear member meshing with both the first and second driven gears; a planet stud supporting the planet gear member; and a planet stud supporting arm mounted on said second shaft with freedom to oscillate relatively to the driven gears.

7. A planetary detaching roll drive comprising the combination with a comb cylinder shaft and a roll drive gear, of a compound planet gear meshing with such gear, a rock shaft and a crank thereon supporting the planet gear, a second compound gear rotatably mounted on the rock shaft, a drive gear secured to the comb cylinder shaft and meshing with the second compound gear, and

a cam secured to the comb cylinder shaft and adapted to effect intermittent oscillation of said rock shaft.

8. A planetary detaching roll drive comprising the combination with a comb cylinder shaft and a roll drive gear, of a compound planet gear meshing with such gear, a second compound gear meshing with the planet gear, a drive gear secured to the comb cylinder shaft and meshing with the second compound gear, and a cam secured to the comb cylinder shaft and adapted to impart orbital motion to the planet gear.

9. A planetary detaching roll drive comprising a roll drive gear, a compound planet gear meshing therewith, a second compound gear meshing with the planet gear, a drive shaft, a gear secured to the drive shaft and meshing with the second compound gear, and a cam secured to the drive shaft and adapted to impart orbital motion to the planet gear.

10. A planetary detaching roll drive comprising a roll drive gear, a compound planet gear meshing therewith, a second compound gear meshing with the planet gear, a drive gear mesh-

ing with the second compound gear, and means for imparting orbital motion to the planet gear.
